(57) **CLAIM**

The ornamental design for a thermometer, as shown and described.

DESCRIPTION

FIG. 1 is a front perspective view of a thermometer constructed in accordance with an embodiment of the present invention;

FIG. 2 is a back perspective view of the thermometer of FIG. 1;

FIG. 3 is a front view of the thermometer of FIG. 1;

FIG. 4 is a back view of the thermometer of FIG. 1;

FIG. 5 is a top view of the thermometer of FIG. 1;

FIG. 6 is a left side view of the thermometer of FIG. 1;

FIG. 7 is a right side view of the thermometer of FIG. 1; and,

FIG. 8 is a bottom view of the thermometer of FIG. 1.

The elements delineated in dashed lines form no part of the claimed design of the thermometer.
